(57) **CLAIM**

The ornamental design for a display screen with graphical user interface, as shown and described.

DESCRIPTION

FIG. 1 is a front view of a display screen with graphical user interface showing our new design;

FIG. 2 is a front view of a display screen with graphical user interface identifying features of FIG. 3; and,

FIG. 3 is an enlarged view of features shown in FIG. 1. The broken line showing of the display screen, text, and graphic features forms no part of the claimed design.

1 Claim, 3 Drawing SheetsFIG. 1

FIG. 3
